Primary Examiner — Ian Simmons*Assistant Examiner* — Dana L Meyrow(74) Attorney, Agent, or Firm — Abelman, Frayne & Schwab(57) CLAIM

The ornamental design for an bottle, as shown and described.

DESCRIPTION

FIG. 1 is a front view showing my bottle design, the rear view being a mirror image thereof;

FIG. 2 is a top plan view thereof shown at an enlarged scale;

FIG. 3 is a bottom plan view thereof; and,

FIG. 4 is a cross-section view taken at the lines 4-4 of FIG. 1, shown at an enlarged scale.

The broken lines in the drawings illustrate the portions of the design that form no part of the claim.
